(57) **CLAIM**

The ornamental design for a clothing care machine, as shown and described.

DESCRIPTION

FIG. 1 is a front perspective view of a clothing care machine, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the portion, '8' in FIG. 1;

FIG. 9 is an enlarged view of the portion, '9' in FIG. 2; and,

FIG. 10 is a cross-sectional view taken along line 10-10 of FIG. 2.

The dot-dot-dash broken lines encircling enlargement portions of the design form no part of the claimed design. The dot-dash broken lines in the figures represent a boundary of the claimed design and form no part of the claimed design. There remaining broken lines illustrating portions of the clothing care machine and environmental structure form no part of the claimed design.
